DRAFT TUBE

Application filed May 8, 1925. Serial No. 28,868.

This invention relates to draft tubes for hydraulic turbines and the like and particularly to draft tubes wherein the flow received in one direction is turned and discharged in another direction at an angle to the first.

The object of the invention is to provide a draft tube which will smoothly and efficiently decelerate the flow within a relatively small space. The smoothness of the deceleration not only helps in increasing efficiency but also avoids any tendency toward vibration sometimes set up by a flow at high velocity or under reduced pressure. The close spacing of a series of turbine units in a powerhouse also frequently limits the dimensions of the draft tube, particularly in transverse width, so that there is no room for extensive lateral spreading of the tube without interference with adjacent units or requiring a prohibitively wide spacing of the units.

I have found that by bending the discharge stream as a whole and at the same time changing its cross sectional form and properly controlling the rate of velocity deceleration throughout the stream, the regular and efficiently smooth turning of the entire flow may be attained within very narrow space restrictions, in a conduit of simple construction.

In the accompanying drawings illustrating the invention

Fig. 1 is a sectional view through a draft tube illustrating the invention.

Fig. 2 is a plan view of the same with successive sectional shapes indicated at corresponding points of the tube, each cross section indicated at I, II, III, IV, V, VI, VII, VIII and IX of Fig. 1 being indicated in outline turned into the horizontal plane.

Fig. 3 is a typical graph showing the velocity of the flow at successive points in the tube.

Fig. 4 is a diagrammatic representation of a comparative straight conical tube having the same velocity values as those in the bent tube of Fig. 1, shown in half section.

Figs. 5 and 6 are views similar to Figs. 1 and 2 but illustrating another form of tube.

Fig. 7 is a vertical section of a modified

form of tube taken on the line 7—7 of Fig. 8.

Fig. 8 is a sectional view taken on the line 8—8 of Fig. 7.

Figs. 9 and 10 are partial diagrammatic views showing the changes in the form of 55 the tube of Figs. 7 and 8 at successive sections indicated on the figures.

Fig. 11 is a diagrammatic development of the line A', G', F', E', D' indicated on Fig. 8. 60

Fig. 12 is a sectional view of a further modified form of tube taken on the line 12—12 of Fig. 13.

Fig. 13 is a sectional view taken on the line 13—13 of Fig. 12, and 65

Figs. 14 and 15 are sectional views on the lines 14—14 and 15—15 respectively of Fig. 13.

In the embodiment of the invention shown in Figs. 1 and 2 the flow leaving the turbine 70 runner enters the draft tube at 20, is turned in the bending portion 21 of the tube and passes out to tailwater through the discharge portion 22.

From the entrance section, designated I 75 at the center line, to the section II the tube is substantially straight and circular in section. Beyond section II the curvature definitely begins and continues with a center line designated II, III, IV, V, VI and VII. 80

Throughout the turn the sectional form progressively changes, as shown in Fig. 2, from substantially circular at section II to a transversely elongated section at VII. The side walls 23 and 24 spread or diverge (Fig. 2) 85

while the inner surface 25 and outer surface 26 of the bend (Fig. 1) at first remain nearly the same distance apart or slightly diverge to III and then gradually converge so as to approach nearer and nearer together. This permits the inner surface to curve gradually with a large radius of curvature and likewise the outer surface 26 curves along a sweeping 90

gradual bend, and the stream between surfaces follows its natural tendency to spread laterally while its inner and outer surfaces converge. Each element of the flow thus smoothly bends and changes in shape in a natural manner and without tendency to set up cross currents or eddies. 95

This change in direction and form of the stream is accompanied by a reduction in the velocity so as to simultaneously convert velocity head into pressure head. At first this deceleration of the velocity may be relatively large and approach closely to the permissible efficient deceleration in a straight draft tube. As the tube curves however the rate of deceleration is reduced throughout the major portion of the bend. As shown in the diagram Fig. 3, for instance, plotting velocity against distance along the center line, the velocity is quite rapidly reduced until near section III the graph begins to curve so as to become less and less steep, indicating a constantly decreasing rate of deceleration. As section VI is approached the graph flexes toward an increase in steepness indicating a slight increase in the rate of deceleration as the bend increases in radius near its end. The shape of the velocity graph of any given tube will depend upon the individual form and curvature of the tube. In general the lower the rate of deceleration, i. e., the flatter the curve, the less will be the likelihood of irregularities in the flow or any separation of the flow from the tube walls. The more rapid the curvature of the tube walls the less will be the tendency of the flow to follow them. Consequently the portions of a bend that are relatively abrupt and of small radius of curvature will have the least deceleration and the more rapidly the radius of curvature decreases the more rapidly will the rate of deceleration decrease.

In the process of decelerating the velocity of flow of water in a passage enlarging in the direction of flow, the angle of divergence of the side walls from the initial direction of flow is much more effective on the elements of the flowing stream which are adjacent to the side walls than it is upon the central portions of the flow which are more remote from the side walls and therefore do not feel the influence of their angle to the same extent. The result is that in a straight, enlarging conduit the central elements of the flow are decelerated much more slowly and less effectively than the elements in contact with the wall, and the result of the enlargement is therefore to set up an unequal distribution of velocity across the conduit, the velocity at the center remaining higher than at the side wall. If the angle of divergence of the side walls is too great, this unequal distribution of flow may be carried so far as to result in eddies or backward flow around the walls with a consequent loss of energy and inefficient deceleration.

In a conduit containing a bend or elbow, a similar effect is caused even when the area of the conduit remains constant in passing around the elbow. The effect of the bending of the stream is to set up centrifugal forces which build up an increase of pressure

around the outside of the bend and cause a reduction of pressure at the inside of the bend with a consequent tendency toward an increase of velocity at the inside of the bend and a decrease at the outside, so that the effect of a bend in a channel is to cause a greater and greater inequality of velocity distribution as the flow passes around the bend. If the curvature of the conduit is too rapid, the flow will tend to leave the inner surface of the bend leaving eddies or backward flow in this region, or an effect similar to too rapid enlargement of a straight conduit. It is therefore seen that the effect of gradual enlargement in a conduit and the effect of curvature of a conduit without enlargement are similar in creating non-uniform distribution of velocity transverse to the flow.

Since the effects of enlargement and of curvature of the centerline of the conduit are thus in general similar in creating non-uniform distribution of velocity across a section, it follows that when we desire both to decelerate velocity and to turn it around a bend at the same time, it is necessary to limit the rate of enlargement in proper relation to the rate of curvature of the conduit so that the two effects when superimposed will not result in extreme variation of velocity across the conduit or the creation of backward flow or eddies.

As the flow progresses around a bend or elbow of the conduit, therefore, it is necessary progressively to decrease the rate of deceleration in passing from the entrance to the discharge section of the bend and at the point where the greatest distortion of flow would be caused by the curvature of the conduit, for instance, adjacent the discharge end of the elbow, it is necessary to reduce the rate of deceleration to a very low value approaching a condition of constant velocity. After the flow has been deflected into a new direction, the rate of deceleration can then be gradually increased so that at points more distant from the elbow the rate of deceleration can approach more and more closely to that permissible in a straight conduit.

In Fig. 4 the successive areas of the tube of Fig. 1 are represented by the radii of equivalent circular sections laid off along a straight center line so as to show the form of the wall of an equivalent straight tube of circular cross section. This indicates a relatively large angle of flare α_1 at entrance which angle begins to decrease at section III and continues this decrease to a point of flexure near section VI after which the angle begins a slight divergence to VII, after which it increases to a substantially constant value α_2 for the straight outlet portion.

To convert velocity head into pressure head it is desirable to have as great a reduction of velocity as possible throughout the tube as a whole. To this end the straight or

substantially straight portions of the tube have a relatively large angle of flare—for instance corresponding to 5° or even 7° in an equivalent straight tube such as indicated in Fig. 4. The bend of the tube has as much velocity reduction as can be effected during the process of deflecting the flow through an angle, consistently with the maintenance of smooth conditions of flow. I have found that while these conditions do not permit a high rate of deceleration at the bend the average permissible deceleration, and consequently the total deceleration, in the bend may be considerable and consistent with the maintenance of highly smooth and efficient flow conditions. In Fig. 4, for instance, the flare of the straight tube walls corresponding to the bend of the tube of Fig. 1 decreases to between 1° and $1\frac{1}{2}^\circ$ and then slightly increases as the end of the elbow is approached and the curvature of the passages decreases. This flare around the curve gives an increase in area between the entrance section II and the discharge section VII so that the discharge area VII is equal to 1.75 times the entrance area II and in general the discharge area of the bent portion of the tube will be from one and one-half to two times the entrance area and the velocity at the discharge VII will be about two-thirds to one-half of the velocity at the entrance section II.

Simultaneously with this increase in area the cross sectional shape of the tube changes to widen out laterally and decrease the distance between the inner wall and outer wall so that the distance b between these walls at the discharge VII is less than the dimension a of the substantially circular entrance section II and in general this dimension b will be not over two-thirds of dimension a , nor less than one fourth of a .

The shape of the bend in plan view (Fig. 2) will vary depending for instance on the available space for the widening of the bend at the turn. Where permissible this lateral spreading may be carried out to comparatively large widths as shown for instance in Figs. 8 and 13, but the conditions of installation will often make it advisable or necessary to retain the lateral width of the bend within dimensions permitting only a relatively gradual lateral spread. This will be the case when a portion of the draft tube structure is already in place in the plant or where it is desired to modify an existing draft tube so that its form and area transition may be made to conform to the principles here explained.

In the bend shown in Figs. 1 and 2 the tube expands laterally with a moderate increase in width from point to point as indicated by the side surface contour lines 28 and this lateral expansion is such as to give these contour lines 28 an outward convexity away from the axis at the entrance sections I, II, III followed by a flexure leading to a convexity toward the

axis for the sections IV, V, VI and this is succeeded by reverse flexure adjacent section VI to a slight convexity as the bend merges with the final outlet passage 22. The outlet passage 22, as shown in Fig. 2, expands laterally at a lower rate than the lateral expansion of the bend, or as shown for instance in Figs. 8 and 13 the outlet passage will not expand laterally at all.

In case it is permissible to widen the draft tube passage, the same successive area and velocity relations may be maintained around the bend by bringing the inner and outer surfaces 25, 26 closer together. This will reduce the distance from the inner to the outer surface and may change the side contour lines to be generally convex away from the center as indicated in the side contour lines of Figs. 8 and 13.

The inner surface 25 of the bend is shown as arc shaped in section II and flat with transverse straight line elements of increasing length in sections III to VII where it merges into the flat roof 29 of the outlet passage 22. As indicated in Figs. 7 to 15 this inner surface of the bend may be transversely curved instead of flat, this transverse formation being designed to permit sufficient vertical contraction to be provided for the portion of the stream which passes directly downstream in the center of the discharge portion, while at the same time providing enough discharge area for the laterally deflected portions of the stream by increasing the height of the passage as the sides are approached. The resulting formation is characterized by the inner surface of the elbow changing from a shape concave inwardly at the beginning of the bend to a form convex inwardly at the end of the bend, when viewed in planes normal to the direction of flow.

By this combination of changing section shape and similar bending of the flow lines across the tube and the progressive decrease in the rate of deceleration, the flow received at the entrance is turned and has its velocity head converted into pressure head within laterally narrow space restrictions and with maintenance of efficient and smooth conditions of flow. The result is that the draft tube of this invention co-operates with the turbine to increase the net head and the overall efficiency, while at the same time avoiding any tendency to set up vibrations in the water column passing through the tube.

Figs. 5 and 6 are views corresponding to Figs. 1 and 2 and illustrating a modified tube with decreased lateral spreading of the tube around the bend. In these Figs. 5 and 6 the reference numerals of Figs. 1 and 2 indicate corresponding parts by corresponding numerals primed. The inner and outer walls 25', 26' of the bend of this modified tube do not approach each other as rapidly as the

walls 25, 26 of the draft tube of Fig. 1, and the sections III, IV, V, VI and VII of the modified tube are reduced in lateral width, the successive areas and velocities being closely analogous in the two tubes.

In the modification illustrated in Figs. 7 to 11 the draft tube comprises a straight portion 39 receiving the flow and decelerating it and passing it to the curved portion 41 where the flow is simultaneously turned, spread and decelerated. From this curved portion the flow is passed to the outlet portion 42. The bend 41 of this tube has a wide lateral spread of the side surfaces 48 (Fig. 8) and the inner surface 45 and the outer surface 46 approach toward each other at a comparatively rapid rate so that the central dimension b at the end of the bend is less than half the diameter a at the entrance. The inner surface 45 forms part of a bell shaped flare formed by the spreading of the walls of the bend and curving smoothly downwardly and outwardly to a rounded ridge or inverted crest formation 50 of generally oval shape as indicated by the dot and dash lines 50 of Fig. 8. Beyond the end 50 of this flare the curvature of the surface continues to form an upwardly and outwardly inclined roof surface 52.

The floor 51 of the draft tube is flat and the lowermost portion 50 of the flare approaches closely to the floor at the center as indicated in the developed view of Fig. 11 where the contour surface 50 with relation to the floor 51 is shown laid out in a plane. The vertical dimensions b are indicated at the points A', G', F', E' and D' corresponding to these points as indicated in Fig. 8. This flare formation is also shown in the vertical sections of Fig. 9 showing successive sectional contours on each side along the radial planes OC, OD'D and OE'E and the combining radial and transverse planes OF'F and OG'G. These sections show the rapid flaring of the bend at the successive sections and the continuation of the flare to form the roof surface 52 continuing the lateral expansion and merging with the roof surface 53 of the outlet portion 42. As shown in Figs. 7, 8 and 9 the roof surface 52 on each side expands and passes downwardly around the crest line 50 and with transverse elements (Fig. 9) having an upward and outward inclination beyond the line 50. The flow lines are thus spread widely on each side of the bend and are simultaneously turned into the outward direction.

The wide spreading of the bend 41 as above described permits the turning and decelerating of the flow to be made within a short vertical distance, the inner and outer walls 45, 46 converging toward each other so as to follow the flow closely and avoid any separation of the flow lines from the surface of the tube. The rate of deceleration around the bend is carefully controlled as explained in connection with Figs. 1 to 4 so as to progressively

lower the rate of deceleration during the turning of the flow. The deceleration and turning of the flow is thus smoothly and efficiently accomplished within moderate lateral dimensions and very short vertical distance and without any upstream extension of the tube. 70

The outwardly directed flow from the bend is received along the line H—H (Fig. 8) by the outlet portion 42 having the floor 51 and roof 53 shaped as shown in Figs. 7 and 8 and the successive sections H—H, I—I and K—K of Fig. 10. The downward bulge of the surface 50 gives a downward or inverted bulge or ridge to the roof 53 at the section H—H and the tendency of successive sections of the passages is to flatten out this bulge toward the outlet end of the tube. A pier member 55 is provided in the outlet section as shown and extended any desired distance toward or even into the bend 41 of the tube. 75

In Figs. 12 to 15 a further modification is shown with a still further widening of the bend of the tube, the reference numerals of Figs. 7 to 11 being primed and connected to corresponding elements of Figs. 12 to 15. In this modification of Figs. 12 to 15 the rounded ridge of the inverted crest 50' is substantially horizontal throughout and the roof surface 53' continuing from this ridge is bulged downward at the center, as indicated in Fig. 15, and is inclined upwardly and outwardly away from the substantially horizontal floor surface 51' as indicated in Fig. 12. The flare surfaces extend outward so widely that a transverse section such as 14 at the center of the tube shows these surfaces merging with and tangent to the roof surface 52' closely adjacent the side surfaces 48'. From this section 14 toward tailwater the roof surface 52' on each side will incline upward at a moderate angle as in the draft tube of Figs. 7 to 11, and as indicated in Fig. 15 forms a continuation of the roof surface 53'. 90

The widely spread form of tube shown in Figs. 7 to 15 is advantageous in that it permits a large portion of the flow to have its meridian velocity components diverted into radial or approximately radial directions so that these components are turned outwardly away from the axis on all sides except on the upstream side of the draft tube away from the tailrace. The passage thus approaches an annular form in which the water is permitted to continue its rotation about the turbine axis while it passes outwardly to successively greater distances from the axis. In this way the whirl components of the stream leaving the runner can be efficiently decelerated due to the principle of constancy of momentum, according to which the velocity of whirl will decrease in inverse proportion to the distance from the axis. 95

This widely flaring draft tube is, therefore, particularly applicable to turbines of high specific speed in which the water leaves the runner with considerable whirl components of velocity, and is well adapted to propeller-type turbines. In order to provide conduit area to conduct away the portions of the stream which have been laterally deflected to each side of the tube, the roof 52, 10 52' and 53, 53' of the tube after passing below the downward bulge or inverted crest of the upper and inner surface is then sloped gradually upward and outward until it intersects the side walls, and thus provides a collector passage around each side of the inverted crest of the roof. The roof of the collector at the same time slopes gradually upward towards the tailrace, thus decelerating the laterally deflected portions of the 20 stream.

The draft tube of this invention is also particularly advantageous in not carrying the excavation upstream any farther than necessary, so that the power house foundation 25 is not unduly cut into. In many plants, and particularly in the case of low or moderate head plants where the power house forms part of the dam, any excessive cutting away of the power house foundation is especially 30 objectionable. It is, therefore, often desirable from structural considerations to use a comparatively long radius of the outer surface 26, 26' and 46, 46' of the bend, joining the upstream wall of the vertical portion and 35 the floor of the horizontal portion. It is still more important for hydraulic reasons not to have too short a radius of curvature for the inside surface 25, 25' and 45, 45' of the bend to give a gradual turning of the stream where 40 the velocity is high and the pressure low as is the case along this surface. The radius of the outer surface of the bend must also, of course, not be so long as to impair the proper relative spacing between the inner and outer 45 surfaces and the desired sequence of areas around the bend as pointed out above. The ratio of the radius of curvature r of the inner surface of the bend in the plane of the bend to the diameter a at the beginning of the 50 bend, that is,

$$\frac{r}{a}$$

will be approximately as follows:

55 In a tube having a wide lateral extension in which the low point of the bell extends around through about 180° of circumference, as in Figs. 7 to 15,

$$\frac{r}{a}$$

60 will have a minimum value of approximately .60, and this radius of curvature r should not be substantially less than .60 of the initial diameter in any of these tubes. In tubes having

65 a smaller lateral width such as shown in Figs. 1 to 6,

$$\frac{r}{a}$$

70

may reach values as high as 1.5, corresponding to a long and deep tube so that in most cases the radius r will not greatly exceed the diameter a .

The roof of the side collector passages of 75 Figs. 12 to 15, beginning just upstream from 52' in Fig. 14, slopes upward toward the tailrace in straight lines making an angle of about ten degrees with the floor, an angle which is consistent with efficient deceleration 80 of the flow. When the downstream length of the discharge passage is greatly restricted this angle can be slightly increased but should not exceed about 15° to avoid loss of head and inefficient deceleration. The central portion of the roof as shown at 53' in Fig. 12 slopes upward at a similar angle; but since the side portions begin farther upstream the roof at either side of the discharge passage 85 will have reached at the section shown by Fig. 15 a higher elevation than at the center; so that in Fig. 15 and other succeeding sections between Fig. 15 and final discharge the horizontal discharge passage will have a 90 downwardly convex roof; while in Fig. 12 and sections parallel to Fig. 12 the roof will have straight line contours inclined to the floor at a small angle.

In addition to the pier member 55' in the 95 draft tube of Figs. 12 and 13 stay vanes 60 may be added to support the roof from the floor of the draft tube, these stay vanes having flange end portions 61 embedded in the concrete of the substructure. The stay vanes 100 are formed and positioned to offer a minimum 105 resistance to the flow and are preferably placed in substantially semi-circular formation adjacent the downwardly directed crest 50 or 50'.

110 While this invention has been illustrated and described in connection with a vertical shaft turbine and with the draft tube turning the flow toward the horizontal direction, it is obvious that the invention may be used 115 in connection with turbines having inclined or horizontal shafts and is not confined to the specific embodiments shown and described.

120 In a horizontal shaft single or double runner turbine the entrance portion of the tube will in general be horizontal and the discharge portion directed vertically downward. This form of tube is advantageous in its structural simplicity, minimizing the cost of 125 form work when moulded in concrete, and the weight and dimensions when built of metal.

I claim:—

130 1. A draft tube comprising a bent portion

increasing in cross sectional area at a decreasing rate in the direction of flow.

2. A draft tube comprising a bent portion increasing in cross sectional area at a continuously decreasing rate in the direction of flow.

3. A draft tube comprising a bent portion increasing in cross sectional area at a decreasing rate in the direction of flow and with decreasing distance between the inner and outer surfaces of the bend.

4. A draft tube comprising a bent portion increasing in cross sectional area at a decreasing rate in the direction of flow and with constantly decreasing distance between the inner and outer surfaces of the bend.

5. A draft tube comprising a bent portion increasing in cross sectional area at a decreasing rate in the direction of flow and with the radius of curvature of the inner surface of the bend not less than six-tenths of the diameter of the tube at the beginning of the bend.

6. A draft tube comprising a bent portion increasing in cross sectional area at a decreasing rate in the direction of flow and with the radius of curvature of the inner surface of the bend not less than six-tenths of the diameter of the tube at the beginning of the bend and the radius of curvature of the outer surface of the bend being greater than radius of curvature of the inner surface of the bend.

7. A draft tube comprising a bent portion increasing in cross sectional area at a decreasing rate in the direction of flow and with decreasing distance between the inner and outer surfaces of the bend, the cross sectional shape of the tube changing from substantially circular at the entrance to the bend to a laterally elongated shape at the outlet of the bend.

8. A draft tube comprising a bent portion increasing in cross-sectional area at a decreasing rate in the direction of flow, and a discharge portion increasing in cross-sectional area at an increased rate.

9. A draft tube comprising a bent portion increasing in cross-sectional area in the direction of flow at a decreasing rate, said rate reaching a minimum value near the discharge end of said bent portion.

10. A draft tube comprising a bent portion followed by a discharge portion, the cross-sectional area of said tube increasing in said bent portion at a progressively decreasing rate in the direction of flow until the rate reaches a small minimum value near the end of said bent portion, the area then increasing at an increased rate in the discharge portion.

11. A draft tube comprising a bent portion followed by a relatively straight discharge portion, said tube having cross-sectional areas such that in an equivalent straight conical tube having circular areas equal to those of said tube at equal distances measured along the respective centerlines the

angle between the wall of the equivalent straight tube and its centerline will progressively decrease from an initial value of not less than from 5° to 7° to a minimum value, at a point nearly corresponding to the end of the bent portion, of approximately $1\frac{1}{2}^{\circ}$, said angle then increasing in the discharge portion to at least 7° .

12. A draft tube comprising a bent portion at first increasing in cross sectional area at a decreasing rate in the direction of flow and then increasing in cross sectional area at an increasing rate before the end of the bend is reached.

13. A draft tube comprising a bent portion at first increasing in cross sectional area at a decreasing rate in the direction of flow and with decreasing distance between the inner and outer surfaces of the bend and then increasing in cross sectional area at an increasing rate before the end of the bend is reached.

14. A draft tube comprising a bent portion at first increasing in cross sectional area at a decreasing rate in the direction of flow and with constantly decreasing distance between the inner and outer surfaces of the bend, and then increasing in cross sectional area at an increasing rate before the end of the bend is reached.

15. A draft tube comprising a bent portion increasing in cross sectional area at a decreasing rate in the direction of flow so that the discharge area at the outlet of the bend is from $\frac{1}{2}$ to twice the area, at the entrance to the bend.

16. A draft tube comprising a bent portion increasing in cross sectional area at a continuously decreasing rate in the direction of flow so that the discharge area at the outlet of the bend is from $\frac{1}{2}$ to twice the area of the entrance to the bend.

17. A draft tube comprising a bent portion increasing in cross sectional area at a decreasing rate in the direction of flow and with decreasing distance between the inner and outer surfaces of the bend so that the discharge area at the outlet of the bend is from $\frac{1}{2}$ to twice the area at the entrance to the bend.

18. In a draft tube a bent portion of substantially circular cross section at entrance and laterally elongated shape at discharge, the inner and outer surfaces of the bend continuously approaching each other in the direction of flow so that the smallest distance across the discharge is not more than two-thirds of the diameter of the entrance and the greatest height of discharge is materially less than the diameter of the entrance, said inner surface having a radius greater than the radius of said entrance.

19. A draft tube comprising a substantially straight portion, a bent portion having gradually curved inner and outer surfaces continuously approaching each other in the

direction of flow and with laterally spreading sides, and a discharge portion having the continuations of said inner and outer surfaces diverging from each other, the cross-sectional area within said bent portion increasing at a decreasing rate in the direction of flow, and then increasing at an increase in rate in passing from the bent portion into the discharge portion.

20. A draft tube comprising a substantially straight portion, a bent portion having gradually curved inner and outer surfaces continuously approaching each other in the direction of flow and with laterally spreading sides, and a discharge portion having the continuations of said inner and outer surfaces diverging from each other at an angle of not over 15° while the side surfaces of said discharge portion are substantially parallel.

21. In a hydraulic turbine installation a draft tube having a vertical entrance and horizontal discharge, the entrance portion comprising a surface flaring outwardly from its axis, the downstream portion of said surface curving downwardly and outwardly in meridian sections to a point of minimum elevation and then rising again so as to form an inverted crest, said crest extending, with uniform minimum elevation, circumferentially around the axis of said entrance portion so as to subtend an angle of at least 180° at said axis, and the upstream portion of said surface smoothly curving from the entrance direction to the horizontal discharge direction with a radius of curvature not less than the radius of curvature of the downstream portion.

22. A draft tube comprising a vertical entrance portion and a horizontal discharge portion; said vertical portion having on its downstream side an outwardly flaring surface of revolution extending around the axis of the vertical portion through an angle of at least 180° ; and said horizontal portion having a flat horizontal floor and having a roof surface composed of straight line elements sloping diagonally upward toward the discharge at a small angle to said floor, and the upstream portion of said surface smoothly curving from the entrance direction to the horizontal discharge direction with a radius of curvature not less than the radius of curvature of the downstream portion.

23. A draft tube comprising a vertical entrance portion and a horizontal discharge portion, said vertical portion having on its downstream side an outwardly flaring surface of revolution extending around the axis of the vertical portion through an angle of at least 180° , and said horizontal portion having a flat horizontal floor and having a roof surface composed of straight line elements sloping diagonally upward from the end of said surface of revolution toward the discharge at a small angle to said floor, and the

upstream portion of said surface smoothly curving from the entrance direction to the horizontal discharge direction with a radius of curvature not less than the radius of curvature of the downstream portion.

24. A draft tube comprising a vertical entrance portion and a horizontal discharge portion, said vertical portion having on its downstream side an outwardly flaring surface of revolution extending around the axis of the vertical portion through an angle of at least 180° , and said horizontal portion having a flat horizontal floor and having a roof surface composed of straight line elements sloping diagonally upward toward the discharge at an angle of not over 15° to said floor.

25. In a hydraulic turbine installation a draft tube comprising an entrance passage having a vertical axis and a horizontal discharge passage connected by a bend or elbow portion, said bend being formed with the outer part of its surface curving with gradual curvature (or large radius curve) into the floor of the discharge passage and with the inner part of the surface curving downwardly and outwardly to a point of minimum elevation and then sloping upwardly and outwardly to form an inverted crest, said crest extending, with uniform minimum elevation, circumferentially around the axis of the entrance portion so as to subtend an angle of at least 180° at said axis.

26. In a hydraulic turbine installation a draft tube having directions of entrance and discharge approximately at right angles and comprising a bent or elbow portion followed by a substantially straight discharge section, the portion of its surface toward the inside of the bend being so formed that in passing around the bend from entrance to discharge said portion of the surface gradually changes from being inwardly concave to inwardly convex when considered in planes normal to the direction of flow and said inwardly convex surface continuing downstream completely to the discharge end of the discharge section to form a relatively long and gradually enlarging discharge passage.

27. A draft tube comprising vertical and horizontal portions of generally elbow formation, said horizontal portion having its roof surface curved when cut by a substantially vertical transverse plane, to provide an inverted ridge, said ridge extending completely to the discharge end of the draft tube so that the final discharge section of the tube has a roof surface of varying height.

28. A draft tube comprising vertical and horizontal portions of generally elbow formation, said horizontal portion having its roof surface curved when cut by a substantially vertical transverse plane, to provide an inverted ridge substantially at the central plane of the horizontal portion, the bottom

surface of said ridge sloping gradually upward in substantially straight lines to the discharge end of said horizontal portion so as to subtend an angle of not over 15° to the 5 floor of said horizontal portion.

29. A draft tube having horizontal and vertical parts, said horizontal part being of greater depth near one of its sides than at other points disposed progressively inwardly 10 from a point near said side, and said varying depths being bounded by a relatively smooth and continuous surface in a direction transverse to the flow, and the roof and floor of said horizontal part diverging from each 15 other in a downstream direction at angles nowhere exceeding substantially 15° in order to provide a relatively long gradually enlarging discharge passage.

30. A draft tube having horizontal and vertical parts, said horizontal part being of greater depth near one of its sides than at other points disposed progressively inwardly 20 from a point near said side, and said varying depths being bounded by a relatively smooth and continuous surface in a direction transverse to the flow, and said surface being substantially straight in the direction of flow and the depth of the discharge portion of the horizontal part gradually increasing in 25 the direction of flow so that the upper and lower surfaces diverge from each other at an angle nowhere exceeding 15° .

31. A draft tube for a hydraulic turbine comprising an entrance portion directed in 35 the direction of axial discharge from said turbine, and a discharge passage directed substantially perpendicularly to said entrance portion, the walls of said discharge being connected to the walls of said entrance portion by surfaces of smooth and continuous curvature to form a generally elbow shaped 40 passage, said discharge passage having a dimension measured in a direction parallel to the turbine axis which is less at a point near the central plane of the elbow than at a point 45 laterally displaced from said plane and near a side of said passage, and said discharge passage being of substantial length in the direction of flow, its length from the point 50 of least dimension parallel to the turbine axis and the discharge end of the passage being at least equal to the distance of said point from the turbine axis.

32. A draft tube for hydraulic turbines, 55 comprising entrance and discharge passages, the roof of said discharge passage being substantially gradually inclined downwardly from opposite sides toward the center so that said discharge passage in transverse section substantially gradually and smoothly decreases in depth toward the center, the length 60 of said discharge passage from its point of minimum depth to its discharge end being substantially greater than its greatest depth.

33. A draft tube comprising a bent portion

followed by a relatively straight discharge portion, said tube having cross-sectional areas such that in an equivalent straight conical tube having circular areas equal to those of said tube at equal distances measured along 70 the respective centerlines the angle between the wall of the equivalent straight tube and its centerline will progressively decrease from an initial value of not less than from 5° to 7° to a minimum value at a point nearly corresponding to the end of the bent portion, said decrease in angle from initial to minimum value amounting to at least 5° , and said angle then increasing in the discharge portion to at least 7° .

34. In a hydraulic turbine installation a draft tube comprising an entrance passage having a vertical axis and a horizontal discharge passage connected by a bend or elbow portion, said bend being formed with the outer part of its surface curving with gradual curvature (or large radius curve) into the floor of the discharge passage and with the inner part of the surface curving downwardly and outwardly to a point of minimum elevation and then sloping upwardly and outwardly to form an inverted crest, the depth of the passage at said point of minimum elevation being less than one-half the 85 diameter of the entrance passage.

35. In a hydraulic turbine installation a draft tube comprising an entrance passage having a vertical axis and a horizontal discharge passage connected by a bend or elbow portion, said bend being formed with the outer part of its surface curving with gradual curvature (or large radius curve) into the floor of the discharge passage and with the inner part of the surface curving downwardly and outwardly to a point of minimum elevation and then sloping upwardly and outwardly to form an inverted crest, the maximum depth of said discharge passage at its 90 smallest section being materially less than one-half the width of said smallest section.

36. A draft tube comprising vertical and horizontal portions of generally elbow formation, said horizontal portion having its roof surface curved when cut by a substantially vertical transverse plane, to provide an inverted ridge, said inverted ridge when cut by a vertical longitudinal plane having a straight contour for a substantial distance in the direction of flow in order to provide a relative long gradually enlarging discharge passage.
